UNITED STATES PATENT OFFICE

PAUL DANCKWARDT, OF NEAR DARDANELLE, ARKANSAS.

PROCESS OF PRODUCING OXYGEN.

1,124,304.

Specification of Letters Patent.

Patented Jan. 12, 1915.

Application filed March 4, 1914. Serial No. 322,281

To all whom it may concern:

Be it known that I, PAUL DANCKWARDT, a citizen of the United States, residing near the city of Dardanelle, county of Yell, and State of Arkansas, have invented a certain new and useful Process of Producing Oxygen, of which the following is a specification.

My invention relates to a process of making oxygen. It is based on the same reaction as the old well known method of Tessié du Motay. This method has been improved from time to time and is holding its own in such improved forms still to-day, against the newer mechanical and electrolytic processes. However, it was never adapted to the manufacture of oxygen on a very large scale for the reason that an immense number of retorts and a great amount of labor were required to work it, and that it is not a continuous process.

My present invention does away with these bad features. This process can be conducted on any scale in a single apparatus and works without intermittance and very little attendance. Though it is a true statement, that an excess of the alkali hydrate over the amount Tessié du Motay's formula prescribes, slackens the reaction when the process is conducted in the old fashion of nearly normal pressure, and an excess of alkali has besides the disadvantage of softening the mixture and making it impenetrable to the gases, I have found that, if a very large excess of alkali or some other diluent (or solvent) is given, so that the whole mass becomes fluid and the air and steam are then introduced finely divided and under pressure and at a some-higher temperature, the reactions are much accelerated, and using such a fluid mass, it is then possible to make the process continuous, by submitting simultaneously part of the mass to an oxidizing, the other part to a reducing treatment, while the gases evolved are kept separate. This way I obtain also the advantage of pure oxygen instead of 80-85% by the older methods.

In the accompanying drawing: Figure 1 is a vertical section of one form of an apparatus for carrying my invention into effect, and Fig. 2 a horizontal section.

The main part of the apparatus, wherein the reactions are taking place, consists of 2 iron cylindrical vessels or chambers 1 and 2, set in brickwork 3. They are closed on

top, except for manholes 39 and 4 and outlet pipes 5 and 6 for the gases, the first one 5 of which, has a valve 38 near its other extremity, to prevent any water from entering the chamber 1, as long as not sufficient pressure is on it. This valve could be dispensed with by placing the chambers at a sufficiently high level to attain the same result. At their bottoms the two chambers 65 communicate with each other in a double way through pipes 7 and 8 and openings in the bottom plates of the chambers. From the central holes of the bottom plates, pipes 9 and 10 protrude into the interior of the 70 chambers. Further, each chamber contains a round perforated iron pipe, marked 11 and 12 respectively, which reach with their extensions 13 and 14 through the shells of the chambers in an airtight way. The outside parts of these extensions are joined to other smaller pipes 15 and 16 respectively. The larger pipes 13 and 14 are provided with valves 17 and 18 for regulating the pressure. All four pipes serve for the purpose of introducing gases and vapors. Pipes 5 and 6 are provided with manometers 19 and 20.

The apparatus to the right of the drawing represents one of my power apparatus, 85 as patented by be formerly, in a somewhat modified form to suit the conditions of this case better. The object of putting it in, is to recover the largest part of the heat of the gases in the form of power, after they leave 90 the reaction chambers and also, to recover all and any particles of the chemicals that might be carried to waste otherwise. This apparatus, set in brickwork 35, consists of a bottom box 21 with supply pipe 22 and 95 the top box 23, both boxes communicating with each other through the large pipe 24 and the smaller pipe 25 together with the turbine 26. The top box 23 is provided with an outlet pipe 27 for gases and steam. In 100 the interior of pipe 24, near its bottom end, a perforated ring pipe 28 is placed, which connects with the pipe 5 leading to one of the reaction chambers. The top of the power apparatus supports a condenser 29, to which 105 leads the pipe 6 of the other reaction chamber. An outlet pipe 30 attached to the condenser serves for the purpose of conducting the oxygen from the condenser into the lower part of a cylinder 31, while another 110 pipe 32 conducts the condensate from the condenser into the pipe 25 of the power ap-

paratus. Pipes 36 and 37 serve for the cooling water supply. The cylindrical vessel 31 is closed airtight, and has an outlet pipe 33 for the oxygen, and a water supply pipe 34. In order to carry out my invention in this apparatus I first introduce through pipe 13 and branch pipe 15 air, freed of carbonic acid and heated to at least 500° C., and through pipe 14 and branch pipe 16 equally heated steam and continue this, until the whole apparatus and the brickwork are well heated up. I then open the manholes 39 and 4 and introduce through them a mixture, previously melted in a suitable furnace, of pyrolusite (manganese dioxide) or a manganite, such as calcium manganite or manganate, and sodium hydroxid or some other diluent in such proportions that the mixture is well fluid at the temperature to be applied during the process. This temperature is variable according to the particular substance used as a diluent. Using as such an excess of sodium hydroxid, the temperature ought to be at least 500° C. If, however, the potassium hydroxid, or sodium or potassium nitrite is used, the temperature may be lower, while with an alkali carbonate, phosphate, or borate it must be higher. The temperature also depends upon the proportion, that is the amount of excess of hydroxid used. More of this substance will require a lower, less a higher temperature, for keeping the mixture at the proper degree of fluidity. The same applies to the varying amounts of other diluents used. I have found out that 2-3 times the amount of sodium hydroxid than the formula of Tessié du Motay demands is perfectly sufficient to keep the mixture fluid. Proper mixtures with other diluents are: 1 part pyrolusite + $\frac{1}{2}$ parts NaOH + 1 to $\frac{1}{2}$ parts NaNO_2 ; or 1 part pyrolusite + $\frac{1}{2}$ parts NaOH + 1 part borate or phosphate; or 1 part pyrolusite + 2 parts NaOH + $\frac{1}{2}$ parts Na_2CO_3 . With carbonate it is advisable to melt it first with the pyrolusite, then add the NaOH. Instead of pyrolusite may be used any other oxid of manganese, or a manganite, as for instance calcium manganite or a manganate, more or less than the above amounts in accordance with the contents in manganese and impurities. The above examples do, of course, not cover all the proportions suitable for the success of the process. The reactions are probably exactly the same as those of Tessié du Motay. The additions act only as diluents or solvents making it possible to bring the mass finely divided into intimate contact with the air and steam. As much of the mixture must be introduced as will fill both chambers about half, when no gas is introduced. As soon as the air and steam are turned on with their full pressure, which is such as to overcome the resistance of the bath itself, the height of which may be va

ried, plus that of the column of water in the power apparatus or the cylinder 31, the level of the molten mass is above the open ends of the central pipes 9 and 10. I now open valve 38 and then close the manholes, whereby the gases are forced through the power apparatus and the steam and oxygen through the condenser 29 and the cylinder 31 respectively. As no water so far has been put into the latter devices, the gas and steam find very little resistance besides that encountered in passing through the molten chemicals. As soon as the pressure is fully on, I begin filling the power apparatus with water as explained in my other patents, and also the cylinder 31, the latter to be about three-quarters full. In the meantime I have turned on the cooling water to the condenser. When the required amount of water has been run into the power apparatus, I observe the pressures as indicated by the two manometers. If manometer 20 shows less pressure than manometer 19, more water must be run into cylinder 31 through pipe 34, in the opposite case the reverse has to be done. For the water in this cylinder serves the purpose of regulating the pressure in chamber 2 so that it equals that in chamber 1. The same result could be attained by a pressure regulating valve on pipe 30, but I prefer this arrangement, as it is safer and allows of closer regulation. Also the cold water kept in the cylinder helps to condense the last traces of steam contained in the oxygen.

I will now explain the functions of the communication pipes 7 and 8 more fully.

If the level of the molten mass in both chambers stands, while no gas was introduced, at about a height indicated by the dotted line $x-y$, it will, when the air and steam are introduced at their proper pressure, raise to the line $v-z$, because a large amount of gas and steam will be continually entangled with the molten particles of the fluid chemicals. But as no gases can get into the vertical pipes 9 and 10, (for they follow the law of gravity—upward in this case) the result will be that we have in pipes 9 and 10 a column of material which is considerably heavier than the average mixture in the chambers outside of the pipes. Consequently, there arises a tendency of the mass in the pipes to press downward, while from the lowest points on, where gas and steam are introduced—at pipes 15 and 16—and from the level of the perforated pipes 11 and 12 there exists a pressure upward. The resulting movement of the fluid mass is then: downward in the central pipes and following further the bend of the pipes, until the mass reaches the lowest points where it meets the first gas or steam, mingles with them and forms now a lighter mixture and escapes upward above the bottoms of the

chambers, where it spreads out mingling with more gas or steam respectively. It travels now farther up with a large volume of gas or steam, until it reaches the spaces above the pipes, where it can free itself of the gas or steam, which escape, while the now again heavier mass sinks down into the vertical pipes to continue its way. Thus there is established a continuous flow of material from one compartment to the other, while the gases introduced or formed are led off separately for further treatment. Now, as into the left hand chamber only air, or air enriched in oxygen, is introduced, here only the following reactions can take place:

that means: oxygen is continually being absorbed by the chemicals, and that which is not absorbed escapes together with the nitrogen of the air and the steam formed, while in the right hand chamber, where only steam is introduced, the following reaction takes place exclusively:

Thus the compressed air has a bifold effect: First it oxidizes continually the reduced material coming from the oxygen chamber, and at the same time establishes a circulation of material from around the eccentric hole on the bottom of the air chamber to the surface, from where it passes down through the vertical pipe, etc., into the other chamber, while the steam introduced into the other chamber works the fluid in the opposite direction, moving material impoverished in oxygen into the air chamber. Both agencies thus assisting each other, there is created a very lively circulation and agitation and each gas finds ready material enough to enter into reaction with. The oxygen mixed with an excess of steam escapes through pipe 6 and on both passing through the condenser 29 the steam and particles of chemicals carried over are condensed and the solution flows from the bottom of the condenser continually into the pipe 25 of the power apparatus by way of the connecting pipe 32, where it replenishes the water which continually evaporates from it and escapes through pipe 27 in the form of steam. That part of the air not decomposed in the air chamber, together with steam formed, escapes through pipe 5 into the bottom part of the power apparatus, where it mingle with the water, thus surrendering any particles of chemicals that may have been carried over to that body of water. As the air holds considerable heat,

there is a continual generation of steam taking place, in this apparatus, which assists in forcing the water upward thus creating considerable amount of power, when passing back through the turbine. At the same time 70 the chemicals to be recovered from it, become more and more concentrated in it, and when sufficiently concentrated, may be recovered from it by further evaporation in pans, while fresh water takes the place of 75 the withdrawn concentrated brine.

I might use instead of such a power apparatus a common condenser, but would not have the benefit of cheap power and cheap concentration. As to the air used in the 80 process I will remark that it ought to be freed of considerable amounts of carbonic acid, at least in those cases where a hydroxid is used alone as a diluent. It may be introduced also in the shape of air enriched in 85 oxygen by some preliminary process. The steam, if exhaust steam, ought to be freed of oil.

As is obvious from the drawing, no fire place is provided for keeping the reaction 90 chambers and their contents hot, though there might be added flues in the brickwork, through which the hot combustion gases from some suitable furnace might be conducted. If, however, the air and steam are 95 superheated enough, sufficient excess heat can be introduced with them to fully cover any loss by radiation or otherwise.

I claim:

1. The process of producing oxygen, 100 which consists in heating a mixture containing alkali metal manganate or substances that will form this by heat, and one or more other substances forming a diluent, until the mass is fluid, introducing under pressure 105 into this mass air and steam in such a way that the gases cannot mingle with each other, the pressure of the gases being materially greater than that due to the resistance of the molten mass, and collecting the 110 gases separately.

2. The process of producing oxygen, 115 which consists in forcing simultaneously heated air and superheated steam into a molten fluid mass containing an oxid of manganese and a base to form a manganate, besides a diluent which makes it easily fusible, in such a way that the gases resulting can be recovered and used separately.

3. The process of producing oxygen, 120 which consists in forcing simultaneously heated air and superheated steam into different portions of a molten fluid mass of an alkali metal manganate or substances that will form such under the conditions, 125 mixed with a diluent, to make it more easily fusible, and keeping the gases formed separate, so that the oxygen may be obtained in a pure state.

4. The process of producing oxygen, 130

which consists in melting an oxid of manganese with alkali metal carbonate or hydroxid to form an alkali metal manganate and adding to it a diluent, in such proportions as to produce an easily fusible mixture, injecting into different portions of this mixture heated air and superheated steam, so that the resulting gases may be recovered separately.

10 5. The process of producing oxygen, which consists in forcing heated air and superheated steam through different portions of a molten mixture containing an alkali metal manganate and a diluent, the 15 two portions of the molten mass being in free communication with each other and changing their places so that each one is alternately in reaction with the air and the steam, thereby producing oxygen continually and recovering it separately in a pure state.

6. The process of producing oxygen, which consists in forcing heated air, free of carbon dioxid, and superheated steam 25 through different portions of the same body of a molten mixture containing substances that can form a manganate and a diluent, whereby one portion is oxidized and the other portion reduced, and simultaneously

parts of them are continuously caused to 30 change places, continuing the injection of air and steam at the same places, whereby those portions formerly oxidized are now reduced and vice versa, and recovering the gases separately.

35

7. The process of producing oxygen, which consists in forcing simultaneously heated air, free of carbon dioxid, and superheated steam through different portions of a molten mixture containing alkali metal 40 manganate or substances producing the same, and one or more other substances forming a diluent and rendering the mass more readily fusible, thereby causing a flow of the fluid mixture from the place, where 45 oxidation takes place to that where reduction takes place and vice versa, continuing the injection of air and steam, so that alternately the portions of the mixture are oxidized and reduced, cooling the gases for the 50 purposes of recovering any particles of the molten chemicals carried over and to free the oxygen of any steam mingled with it and to recover it in a pure state.
